UNITED STATES PATENT OFFICE.

CHESTER FRANKLIN LEWIS, OF GREENSBORO, NORTH CAROLINA.

HAIR CLIPPER.

Application filed September 18, 1922. Serial No. 586,908.

To all whom it may concern:

Be it known that I, CHESTER F. LEWIS, a citizen of the United States, residing at Greensboro, in the county of Guilford and State of North Carolina, have invented a new and useful Hair Clipper, of which the following is a specification.

This invention relates to hair clippers.

The object of the invention is to provide a hair clipper adaptable for use by an individual on himself by either hand or mechanical means and which is reversible so that either the upper or the lower face may be used.

Another object is to provide a device of this character in which an enclosed spring is arranged so as to be put under initial strain in assembling the clipper without the use of screws or other similar fasteners.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

In the accompanying drawings:—

Figure 1 represents a plan view of the clipper with the top plate removed and the connecting bolt shown in transverse section.

Fig. 2 is a longitudinal section with the handles in side elevation.

Fig. 3 is a detail plan view of the bottom plate.

Fig. 4 is a top plan view of the cover plate with the members thereof supported and arranged in juxtaposition ready for assembling.

Fig. 5 is a detail plan view of the movable blade, and

Fig. 6 is a similar view of the actuating spring detached.

In the embodiment illustrated, the clipper constituting this invention comprises a bottom plate 1 to which is fixed a cutting blade 2 and a handle 3. This handle 3 is preferably detachably connected with the bottom plate as shown at 3^a in Fig. 1 and is equipped with a laterally extending finger grip 4, the handle being disposed at an oblique angle to the plate (see Fig. 3).

Set in the bottom plate 1 is a guide plate 5 on which is mounted to slide a movable

double edged cutting blade 6. A tension spring 7 is set in said guide plate. One end of this spring 7 is set in a recess or groove 8 in the guide plate while the other end of 80 said spring is mounted in a notch or recess 9 in the head 11 of a handle member 10. This handle member head 11 is provided with a radially extending arm 12 which is mounted in a recess 6^a in the rear edge of the movable 65 blade 6. This head 11 is rotatable about a center pin 13 which is carried by the bottom plate 1 and extends upwardly through the guide plate 5 and around which the spring 7 is coiled. This mounting of the coiled 70 spring 7 with one end engaged with the guide plate 5 and the other with the head 11 of the handle 10 operates to maintain tension throughout the stroke of the handle 10. A cover plate 15 fits over the head 11 and is 75 held in place by pins 16 which fit in sockets 17 in said cover plate. This cover plate 15 is constructed in two parts similar to the bottom plate 1, one of which constitutes a fixed cutting blade 2^a detachably secured to 80 top 15.

A cap 18 has threaded engagement with the upper end of the center pin 13 and has its open end flared, which end bears against a flat spring washer 19 mounted on pin 13 85 over head 11 and which operates to hold handle head 11 and blade 6 in place.

This cap 18 has a lateral flange 18^a at its closed end which engages a beveled opening in top 15 and when screwed home, operates 90 in conjunction with pins 16 to hold the top in operative position.

From the above description it will be obvious that with the parts assembled as shown in Figs. 1 and 2 the enclosed spring 7 is so 95 arranged as to be under initial strain in assembling the parts of the clipper so that no screws or other similar elements are required to connect it or to place it under strain as is customary in clippers ordinarily 100 used.

It will thus be seen that a clipper constructed as herein shown and described is reversible so that either the upper or the lower cutting face may be used, the arrangement of the handles in horizontal plane with the cutting blade 6 and at an oblique angle thereto providing for this.

I claim:—

1. A hair clipper comprising upper and 110 lower plates convexo concave at their rear portions and having fixed cutting blades at

- their front ends with a chamber formed between them, a movable cutting blade mounted to reciprocate between said fixed cutting blades, a handle fixed to one of said plates, 5 another handle having a head mounted to rotate in said chamber and engage said movable blade whereby the turning of said head will reciprocate said blade, and a spring to place the parts under tension.
- 10 2. A hair clipper comprising upper and lower plates having cutting blades at their front ends and their rear ends outwardly bowed to form when assembled a chamber between them, a center pin extending through said chamber, a guide mounted on said pin in said chamber, a movable cutting blade mounted to reciprocate on said guide and positioned to cooperate with the cutting blade of the plates, and means or reciprocating 15 said movable blade whereby either cutting face may be presented for use.
3. In a hair clipper, upper and lower plates having cooperating cutting blades at their front ends and their rear ends bowed 20 outwardly to form a chamber between them when assembled, a handle member fixed to said lower plate, a guide mounted in said lower plate, a center pin carried by said lower plate and extending through said chamber, a cap engaged with said upper 30 plate and screwed on said center pin, pins and sockets cooperating to hold said upper plate in operative position, a movable blade mounted to slide on said guide and to cooperate with said fixed blades, a coiled spring 35 carried by said center pin with one end engaged with said guide, a handle having a head mounted in said chamber and engaged with said movable blade, said head being rotatable on said pin, the other end of the 40 coiled spring being engaged with said head, the rotation of the head operating to reciprocate the movable blade.
- In testimony that I claim the foregoing as my own, I have hereto affixed my signature in the presence of two witnesses. 45
- CHESTER FRANKLIN LEWIS.
- Witnesses:
- E. R. LEWIS,
N. L. WARNER.
